WADE E. SACKNER, OF GRAND RAPIDS, MICHIGAN, ASSIGNOR TO GRAND RAPIDS FIBRE CORD COMPANY, OF GRAND RAPIDS, MICHIGAN

PAPER FINISHING CORD

Application filed December 26, 1929. Serial No. 416,410.

The object of the invention is to provide a substantially cylindrical paper finishing edge roll or cord with an effective means of attachment, such means being available independent of any covering whatsoever, thereby avoiding the usual attaching cover or case.

A preferred embodiment of my invention is illustrated in the accompanying drawings, in which:

Fig. 1 is a side elevation view of a section of cord of substantially full size.

Fig. 2 is an enlarged detail end view of the cord appearing in Fig. 1.

The cord is made up of tough paper, preferably a plurality of strips being twisted and crumpled together and delivered through a proper die to make round cord. Then the round cord is introduced into a further forming die which embraces and compresses with very heavy pressure the attaching rib so that the cord has a main body portion 1 and a heavily compressed attaching rib 2. At intervals through the attaching rib are perforations 3. In the size of cord illustrated these are about one inch apart.

These holes are preferably punched through with a pointed punch, although they can be drilled or otherwise formed. The perforations 3 may receive tacks or they may provide the means for suitable stitching of wire or thread to attach the cord in place. The usual cord is covered and the covering means is the attaching means. This is entirely obviated. The result is a great saving in both material and labor. Tacking through the lip likewise is quicker and results in a much better piece of work when finished.

The cord is available in upholstering or in the construction of furniture generally where a round covered bead is desired.

I have shown the preferred form of the cord and indicated the preferred method of manufacture which results in a very strong, compact, attaching lip or rib. By its formation the attaching means is concealed in the depression and the finish is not marred thereby, as is usual where round cord is nailed through the middle part as is sometimes done. This edge roll or cord, however, can be formed, by proper pressure and manipula-

tion, of strips of paper properly compressed without twisting although the twisting is of advantage.

Fibrous material other than paper can be made use of. No doubt certain grades of paper or wood pulp, for instance, might be used, or materials of that character.

With this explanation, I desire to state that I wish to claim the invention in the specific form illustrated and also broadly as pointed out in the appended claims.

Having thus described my invention, what I claim as new and desire to secure by Letters Patent, is:

1. A cord or edge roll formed of strips of paper twisted and molded together with an attaching rib formed integral therewith by molding and condensing from the body of the cord and suitably perforated.

2. A cord or edge roll formed of strips of paper molded together with an attaching rib formed integral therewith by molding and condensing from the body of the cord and suitably perforated.

3. A cord or edge roll of strips of paper twisted and molded together with an attaching rib formed integral therewith by molding and condensing from the body of the cord.

4. A cord or edge roll formed of strips of paper molded together with an attaching rib formed integral therewith by molding and condensing from the body of the cord.

5. A cord or edge roll of paper twisted and molded and having an attaching rib formed integral with one side of a more condensed texture.

6. A cord or edge roll of paper molded and having an attaching rib formed integral with one side of a more condensed texture.

7. A cord of fiber material molded and having an attaching rib, formed integral with one side, of a condensed texture.

In witness whereof I have hereunto set my hand.

WADE E. SACKNER.
